DIRECTIVE RADIO AERIAL SYSTEMS

Sidney Cornbleet, Edgware, England, assignor to The General Electric Company Limited, London, England, a British company

Application September 29, 1952, Serial No. 312,077

Claims priority, application Great Britain
September 28, 1951

6 Claims. (Cl. 343—779)

The present invention relates to directive radio aerial systems of the kind known as reverse feed aerial systems. In reverse feed aerial systems, there are provided a parabolic or other reflector, a length of waveguide or coaxial cable feeder projecting through the reflector from behind, and means for directing radio waves from (or to) the end of the feeder on to (or from) the reflector and thence to (or from) space. Reverse feed aerial systems may be employed either as simple transmitting or receiving aerials, or in duplex operation as common transmitting-receiving aerials. It will be understood that where the operation of aerials is described in this specification with reference to one particular application, for example transmitting, they may equally well be used for either of the other applications.

Usually in reverse feed aerial systems where the reflector is parabolic, the feeder is mainly coaxial with the reflector, so that the direction of waves travelling along the feeder has substantially to be reversed at the end of the feeder in order to direct them on to the reflector. One known method of achieving this is to provide a subsidiary reflector placed opposite the termination of the feeder, and arranged to reflect waves radiated from the feeder termination on to the main reflector, the waves effectively diverging from the focus of the reflector. The subsidiary reflector may be simply a plane plate, or it may be shaped, for example it may be hyperbolic. One objection to this invention is that it is difficult to secure the subsidiary reflector rigidly in position, without introducing mounting parts which interfere unduly with the radiation pattern of the aerial system. This is particularly the case where the aerial system is to be mounted on an aircraft and/or is itself moved rapidly in scanning operations.

Another known arrangement in reverse feed aerial systems, is that known as the "Cutler" feed, which is designed for use where the feeder is a waveguide. In this the end of the waveguide is tapered and projects into a hollow metal box. The box, which is a form of resonant cavity, has apertures in its walls which are directed back towards the reflector, and from which waves are radiated on to the reflector. The apertures, may be sealed with a dielectric material, for example mica in order to seal the waveguide from the atmosphere. A matching slug, which acts in effect as a variable reactance, is provided in the wall of the box opposite the end of the waveguide. This arrangement suffers from the disadvantages that the radio frequency power which may be passed through it is limited, particularly by the taper at the end of the waveguide, which is necessary in order to allow the apertures to be close enough for their phase centres to be practically coincident.

It is an object of the present invention to provide a reverse feed radio aerial system having an improved means for directing waves from (or to) the end of a feeder on to (or from) the reflector.

According to the present invention in a reverse feed directive radio aerial system, the end of the one length

2

of feeder is coupled into an arrangement comprising effectively a closed ring of similar feeder, the electrical distance round the ring being substantially $3\lambda_g/2$ (where λ_g is the wavelength in the feeder of the waves to be propagated therein), and two further equal short lengths of similar feeder coupled to the said ring one at each of the two points which are an electrical distance $\lambda_g/4$ in opposite directions round the said ring from the point at which the said one length of feeder is coupled to it, the two further lengths of feeder have terminations at their ends remote from the said ring directed towards the reflector, through which energy may be passed to and from the reflector.

15 In one system in accordance with the present invention, at least the said one length of feeder is a length of rectangular cross-section hollow waveguide, and the ring and the two further lengths of feeder are also lengths of rectangular cross-section hollow waveguide, the longitudinal axes of the ring and the lengths of feeder 20 lying in one plane to which the shorter dimensions of the cross-sections of the feeder are parallel. The ring of feeder may be circular.

The terminations of the two further lengths of feeder, in the above case where the feeder is rectangular cross-section hollow waveguide, may be rectangular apertures of approximately the same cross-section as the feeder lying symmetrically one on either side of the said one length of feeder.

25 One example of a directive radio aerial system in accordance with the present invention will now be described with reference to the accompanying drawings in which:

Figure 1 shows a general view of the aerial system,
Figure 2 shows a cross-section of the end part of the
30 feeder system in the horizontal plane through its longitudinal axis, and

Figure 3 shows a section at the line III—III in Figure 2.

Referring first to Figure 1 of the accompanying drawings it will be seen that the system includes a length of 40 rectangular waveguide feeder 1 which passes through the vertex of a paraboloidal reflector 2 from behind, its longitudinal axis lying along the axis of the reflector 2. The end 3 of the feeder behind the reflector 2 is coupled in known manner at any desired distance from the reflector

45 2 to an associated transmitter or receiver, or to a common transmit-receive unit if the aerial system is used in a duplex system and has to be coupled to both a transmitter and a receiver. The extent of the feeder 1 beyond the end 3 may be slight if the aerial system is mounted 50 close to the associated equipment, or may be considerable and extend for example the length of a mast at the top of which the aerial system is mounted at the foot of which the associated equipment is situated. The part of the feeder 1 behind the reflector 2 may include one

55 or more rotatable coupling joints along its length so that the aerial system may be rotated about one or more axes. The other end of the waveguide feeder 1 terminates at a feed reversal box 4, a pair of apertures 5 in which, 60 laying one on either side of the feeder 1, radiate or receive energy on to or from the reflector 2. The feed reversal box 4 is described in detail below with reference to Figure 2 or 3 of the accompanying drawings. The aerial system being described is for operation at a

65 band of frequencies centred about the frequency corresponding to a wavelength in space of 3.2 cms. and all dimensions given are for a system for operation at that frequency and will have to be altered correspondingly for other frequencies of operation. The diameter of the reflector 2 at the aperture is 25" and the distance of the apertures 5 from the vertex of the reflector 2 is 10.75",

that difference being equal to the focal length of the reflector 2.

Figure 2 of the accompanying drawings shows a cross-section through the end part of the feeder 1 and the feed reversal box 4, in the horizontal plane passing through the longitudinal axis of the feeder 1. (The term horizontal is used in this description with reference to the position of the system as shown in Figure 1.) The feeder 1 as stated above is a length of rectangular cross-section waveguide, the shorter dimension of the section lying in the plane of Figure 2. In the end part shown in Figure 2 the feeder tapers in the horizontal plane from 0.5" between the inner surfaces of the walls at and beyond the point A, to 0.39" at and beyond the point B. The cross-section tapers uniformly between the points A and B and is constant beyond those points. The longer dimension of the cross-section is invariant and is 1.125" between the inner surfaces of the walls. The walls of the waveguide are .0625" thick.

The feeder 1 terminates at a waveguide junction of the type known as a "rat-race." This consists of a circle of waveguide 10 of the same cross-section as the feeder 1 at its end, the diameter of the inner wall of the circle of waveguide 10, i. e. that of the central pillar 11, being 0.412", and that of the outer wall being 1.042". The electrical distance round the circle of waveguide 10 is $3\lambda_g/2$, where λ_g is the wavelength in the waveguide of the waves propagated in the feeder system. The other arms of the rat-race junction, that is the length of rectangular section waveguide 12 and 13, also terminate at the circle of waveguide 10, the ends of the lengths of waveguide 12 and 13 being an electrical distance $\lambda_g/4$ from the end of the feeder 1. The longitudinal axes of the lengths of waveguide 12 and 13 at their ends are inclined at 60° to that of the feeder 1. The lengths waveguide 12 and 13 curve symmetrically and terminate at their ends remote from the rat-race, at the apertures 5 on either side of the feeder 1, which apertures 5 are directed towards the reflector 2 as hereinbefore described with reference to Figure 1 of the drawings. The feeder 1 has thickened parts 14 at the ends of its longer walls, these thickened parts 14 being shaped as shown so that the outer surfaces 15 form part of the inner surfaces of the lengths of waveguide 12 and 13. The inner surface of the feed reversal box 4 is shaped to form the remaining parts of the inner surfaces of the lengths of waveguide 12 and 13. Dielectric plugs 16, which may for example be of polythene, are fitted into the apertures 5 at the ends of the lengths of waveguide 12 and 13. Shallow steps 17, 0.0625" high are made on the outer surface of the walls of the feeder 1 at the apertures 5, in effect reducing the width of the apertures 5.

Figure 3 of the drawings shows a section at the line III—III in Figure 2, and shows the cross-section of one plug 16 in the vertical plane. The inner surfaces of the upper and lower walls 18 of the feed reversal box 4 are slightly flared towards their ends thereby increasing the longer dimension of the rectangular cross-section, the sloping parts 19 of the walls at the flares making an angle of 19° with the flat parts. In addition flanges 20 are provided on the upper and lower walls of the box 4 beyond the flared parts. These project beyond the ends of the side walls of the box 4 which terminate at the ends of the flared parts. It will be seen that the upper and lower walls 18 of the feed reversal box 4 are 0.125" thick, that is twice as thick as the walls of the waveguide feeder 1. Where the end part of the feeder 1 projects into the feed reversal box 4 a groove (not shown in the drawing) 0.0625" deep is cut in the inner surfaces of the upper and lower walls 18 of the box 4, into which the upper and lower walls of the end of the feeder 1 fit exactly. Where the feeder 1 terminates the inner surfaces of the upper and lower walls of the feeder 1 will then be continuous with the inner surfaces of the upper and lower walls 18 of the box 4.

In operation, electromagnetic waves propagated along the feeder 1, which will normally be in the TE₁₀ mode, are coupled equally into the two lengths of waveguide 12 and 13, and there is substantially no reflection back into the feeder 1. The waves radiated from the two apertures 5 are then of the same amplitude and in phase with one another. Similarly waves reflected on to the apertures 5 from the reflector 2 are passed in phase into the feeder 1 without any reflection back into the lengths of waveguide 10 12 and 13 at the "rat-race" junction.

The apertures 5 are too far apart in the plane of the section of Figure 2, to be considered as coincident as far as the reflector is concerned. If the waves propagated in the waveguide are of the TE₁₀ mode, as is usually the case, this plane is the plane of the electric vector or in other words the E-plane. The perpendicular plane similarly is the H-plane. This separation of the apertures 5 in the E-plane results in the phase centres in the E and H-planes being separated in the feeder 1.

It will be appreciated that a similar system may be constructed if desired using other types of feeder, for example coaxial line feeder.

The steps 17 are provided to give the required narrow beam in the F plane by reducing the width of the apertures 5, but in so doing a mismatch is produced. The plugs 16 are included partly to reduce the mismatch, the length of the plugs 16 and the distance they protrude from the apertures 5 being determined to make them reflectionless, that is so that they do not themselves introduce a mismatch. At the same time they provide some adjustment of the position of the E-plane phase centres such that the E and H-plane phase centres are less separated in the feeder 1 than would otherwise be the case. The flare at the apertures 19 in the H-plane provides a final adjustment of the position of the E-plane phase centres to bring them into coincidence with the H-plane phase centres in the feeder 1. However the flares tend to upset the beam shape in the H-plane, and the flanges 20 are provided to correct this. The explanation given 40 above is a simplification of the problems involved, but it is thought that it provides some indication of the purposes of the various features. In fact the various functions are all inter-related.

I claim:

45 1. A reverse feed directive radio aerial system comprising a reflector, a first length of feeder, for passing electromagnetic waves to and from the reflector, projecting through the reflector from behind, a ring of similar feeder, the length of the electrical path round the ring being substantially $3\lambda_g/2$ (where λ_g is the wavelength in the feeder of the waves propagated therein operation) and the ring being coupled at one point to the end of the first length of feeder, two further short lengths of similar feeder one end of each of which is coupled to the ring at points spaced round the ring in opposite directions by an electrical distance $\lambda_g/4$ from the point at which it is coupled to the first length of feeder, the other ends of the two short lengths of feeder having terminations directed towards the reflector for passing electromagnetic waves to and from the reflector.

55 2. A reverse feed directive radio aerial system according to claim 1 in which the first length, the ring and the two further lengths of feeder are lengths of rectangular cross-section hollow waveguide, the longitudinal axes of which lie in one plane, to which the shorter dimensions of the cross-section are parallel.

65 3. A reverse feed directive radio aerial system according to claim 2 in which the said terminations of the two further lengths of feeder are rectangular apertures of approximately the same cross-section as the feeder, the apertures lying symmetrically one on either side of the first length of the feeder and being directed towards the reflector.

75 4. A reverse feed directive radio aerial system accord-

ing to claim 3 including plugs of dielectric material fitted into the apertures.

5. A reverse feed directive radio aerial system according to claim 1 in which the ring of feeder is in the form of a circle.

6. A reverse feed directive radio aerial system according to claim 1 in which the reflector is paraboloidal and the first length of feeder passes through the reflector at the vertex, its longitudinal axis coinciding with the axis of the paraboloid.
